REFRIGERATING APPARATUS

Graham S. McCloy, East Longmeadow, Mass., assignor to Westinghouse Electric & Manufacturing Company, East Pittsburgh, Pa., a corporation of Pennsylvania

Application April 23, 1938, Serial No. 203,806

8 Claims. (Cl. 62—4)

My invention relates to refrigerating apparatus and more particularly to control means therefor and it has for an object to provide improved apparatus of this kind.

A further object of the invention is to compensate for different rates of heat leakage into a refrigerated chamber due to varying exterior temperatures so that the temperature within the chamber is maintained substantially constant.

A still further object of my invention is to provide an improved control mechanism for a refrigerator that will adjust the temperature of the cooling element in response to changes in temperature exteriorly of the refrigerated zone, which mechanism may embody elements of a conventional gas type thermostat.

Another object of the invention is to provide a thermostat for controlling the operation of a refrigerator and including a single gas type thermostatic element that responds to temperature changes within the refrigerated zone and exteriorly thereof.

These and other objects are effected by my invention as will be apparent from the following description and claims taken in connection with the accompanying drawing, forming a part of this application, in which:

Fig. 1 is a diagrammatic view of a refrigerator controlled in accordance with my invention;

Fig. 2 is a diagrammatic view similar to Fig. 1 and disclosing a second embodiment of the invention; and,

Fig. 3 is a diagram showing the pressure-temperature characteristics of the fluids in the thermostatic element for three different ambient temperatures.

Reference will now be had to Fig. 1 of the drawing wherein I have shown my invention applied to a domestic type refrigerator employing a refrigerating machine of the compressor-condenser-expander type. A refrigerator cabinet indicated at 10 defines a heat insulated zone or chamber 11 from which heat is abstracted by an evaporator 12 which may be constructed in any suitable manner. Refrigerant vaporized in the evaporator 12 is withdrawn through a conduit 13 by means of a compressor 14 driven by a motor 15. The compressed refrigerant gas is discharged through a conduit 16 in a condenser 17 and is cooled in any suitable manner, such as, for example, by means of a motor driven fan 18. Refrigerant liquefied in the condenser is delivered to the evaporator 12 through a conduit 19 having a suitable expansion device 21 connected therein for reducing the pressure of the liquefied

refrigerant to the pressure of vaporization maintained within the evaporator 12.

The motor 15 is supplied with electrical energy from a suitable source indicated by the line conductors L₁ and L₂ under control of a snap-acting switch mechanism 22. The switch 22 defines an element of a gas type thermostat, generally indicated at 23 and including a bellows 24, that moves a main pivoted lever 25 upwardly and downwardly as it expands and contracts. An over-center spring 26 may connect the lever 25 to the switch mechanism 22 for imparting snap action to the switch 22 in a well-understood manner. The pressure within the bellows 24 at which the switch is opened and closed may be determined by a spring 27 which provides a bias on the bellows. The bias of the spring 27 may be varied by an adjusting device indicated at 28. The bellows 24 is connected by means of a conduit 29 to a bulb or reservoir 31 disposed within the refrigerated zone 11 and, preferably, in contact with the evaporator 12 so that its temperature varies with the temperature of the evaporator 12.

In accordance with my invention, means is provided for varying the temperature of the evaporator 12 at which the thermostat mechanism 23 operates the switch 22, in response to changes in temperature exteriorly of the refrigerated zone 11. A second conduit 32 provides communication between the conduit 29 and a second expandable bellows 33 that is disposed within a fluid 34 and container 35. The container 35 is disposed in the atmosphere exteriorly of the zone 11 so that the fluid 34 will expand and contract with increases and decreases in the temperature of the outside atmosphere.

The bellows 33 and 24, the conduits 29 and 32 and the bulb or reservoir 31 define a closed chamber for containing first and second fluids, one of which is a volatile fluid whose pressure varies with the temperature of the evaporator 12 and bulb 31. The second fluid is, preferably, an inert gas whose pressure is substantially unaffected by the temperature of the evaporator 12. The bellows 24 is subjected to the combined pressures of the two fluids. As the bulb 31 defines the coldest portion of the structure containing the two fluids, the liquid portion of the volatile fluid is always present in the bulb 31 and the pressure of the volatile fluid is a function of the temperature of the liquid portion thereof. The second non-condensable fluid or inert gas is diffused with the gas of the volatile fluid and its pressure varies

with expansion and contraction of the bellows 33. As the outside or room temperature increases and decreases, the expansion and contraction of the fluid 34 contracts and expands the bellows 33. Accordingly, the pressure of the inert gas increases and decreases with respective increases and decreases in the temperature of the atmosphere exteriorly of the zone 11. The pressure exerted by the primary or volatile fluid is not affected by room temperature changes as its pressure is a function of the temperature of the liquid portion thereof.

My invention will be best understood by referring to the curves shown in Fig. 3. The curve 15 "A" shows the pressure temperature-characteristics for the primary or volatile fluid employed in the thermostat. The total pressures in the thermostat, or the sums of the pressures of the volatile fluid and the inert gas, for three different 20 ambient temperatures are shown at B, C, and D. The curve B represents the variation in total pressure in the thermostat when the lowest expected ambient temperature obtains. When this 25 condition prevails, the pressure of the inert gas is minimum. The curves C and D show the variations in total pressures for progressively higher ambient temperatures with corresponding progressive increases in the pressure of the inert gas. It will be apparent that, as the ambient 30 temperature increases, the portion of the total pressure which is exerted by the secondary or inert gas is increased, and vice versa.

As an example, any of the inert gases such as, 35 nitrogen, may be used with a volatile fluid such as, sulphur dioxide (SO_2) in effecting the control described heretofore. When a fluid having a low boiling point is employed as a secondary gas, or the gas whose pressure changes with variations in outside temperature, satisfactory operation is 40 provided by the use of sulphur dioxide SO_2 as the primary fluid and dichlorodifluoromethane CCl_2F_2 as the secondary fluid. The latter may be charged at a pressure of 5 lbs. per square inch so that it would provide compensation at evaporator 45 temperature of $-8^{\circ} F.$ and above. The conditions to be fulfilled in the latter combination are that the two constituents are inert toward each other and are not miscible in each other and that the secondary gas be charged into 50 the system at a pressure such that condensation of the gas would not occur at the evaporator temperature at which the machine operates. Accordingly, the secondary gas, or the dichlorodifluoromethane in the example cited, is in a superheated 55 condition at all normal evaporator temperatures.

The thermostat 23 operates to close and open its switch 22 for starting and stopping operation of the compressor 14 when respective predetermined high and low total pressures obtain in the bellows 24.

Operation

It will be assumed that the control thermostat 60 23 is adjusted to initiate and terminate operation of the compressor motor 15 when the pressures obtaining in the bellows 24 are 20 lbs. and 3 lbs. per sq. in., respectively. These pressures correspond to evaporator temperatures of $-2^{\circ} F.$ and 65 $28^{\circ} F.$, when the pressure exerted by the inert gas is at the minimum value determined by the lowest expected room temperature. See curve B. Accordingly, the compressor and motor are 70 started and stopped in response to evaporator temperatures of $28^{\circ} F.$ and $-2^{\circ} F.$, respectively,

when the temperature of the room is relatively low.

An increase in the temperature of the air in the room causes expansion of the fluid 34 in the container 35 and, therefore, contraction of the bellows 33, whereby the inert gas is compressed and its pressure increased. It will be assumed the room temperature increase is such that the pressure of the gas is increased 2 lbs. per sq. in. The control still functions to close and open the switch 22 at 20 lbs. and 3 lbs., respectively, total pressure. As shown by the curve C in Fig. 3, these pressures correspond to evaporator temperatures of $25^{\circ} F.$ and $-10^{\circ} F.$, respectively. The evaporator 12, therefore, is operated at a lower temperature with a high room temperature and compensates for the higher heat leakage into the zone 11 due to the higher room temperature.

A further increase in the ambient temperature 20 effects a further increase in the pressure exerted by the secondary fluid, so that the evaporator is operated in accordance with the pressure temperature characteristics of curve D. As shown by curve D, the temperature of the evaporator, 25 corresponding to 20 lbs. pressure in the bellows 24 is $20^{\circ} F.$, at which temperature the compressor 14 is started. The temperature of the evaporator corresponding to a total pressure of 3 lbs. in the bellows is $-18^{\circ} F.$ at which temperature the compressor is stopped.

The figures which I have employed in connection with the curves in Fig. 3 are approximate and have been used for illustrative purposes only.

It will be apparent from the foregoing description that the evaporator is operated at temperatures which vary inversely with changes in ambient temperature whereby compensation is provided for different rates of heat leakage into the 40 refrigerated zone to maintain the temperature of the refrigerated media substantially constant.

Description—Fig. 2

In Fig. 2 I have disclosed a second embodiment 45 of the invention wherein different means are employed for obtaining the pressure variation in the bellows due to a change in room temperature. The refrigerating system is similar to that shown in Fig. 1 and similar elements are designated by like reference characters. Also, the thermostat is of similar construction to the thermostat structure 23 except for the element which is subjected to room temperature and its contents. Parts common to the thermostats of Figs. 1 and 2 are designated by like reference characters.

In the embodiment shown in Fig. 2, I employ, in addition to the volatile fluid whose pressure varies with evaporator temperature, a gas which is soluble in an absorbing material 41 in amounts bearing a relation to the temperature of such material. The absorbent material 41 is contained in a container 42 that communicates with the bellows 24 and conduit 29 by a tube or conduit 43. As the temperature of the absorbent material 41 increases, gas is driven therefrom and increases the pressure in the bellows 24. Conversely, as the temperature of the material 41 decreases, the gas is absorbed by the material and the pressure in the bellows 24 is decreased. Accordingly, the relation between the total pressure in the bellows 24 and the temperature of the volatile fluid in the bulb 31 is varied for the

purpose of varying the temperatures of the evaporator 12 at which the bellows 24 effects opening and closing of the motor control switch 22. The result of this operation has been described heretofore in connection with Fig. 1 and need not be repeated.

The soluble gas employed in Fig. 2 may be ammonia with calcium chloride as the absorbent. Dichlorodifluoromethane (CCL_2F_2) gas may be 10 employed with oil as the absorbent. Where dichlorodifluoromethane is used as the secondary gas and oil as the absorbent, any volatile fluid may be employed as the primary fluid, provided it is not miscible in the oil to any material degree 15 and that it does not react with dichlorodifluoromethane. Sulphur dioxide SO_2 may be satisfactorily employed as the primary fluid in this combination of fluids. When ammonia gas and calcium chloride are used as the secondary fluid and 20 absorbent, it is necessary that the primary gas is non-absorbent in calcium chloride and inert toward ammonia. Dichlorodifluoromethane may be employed in this combination of fluids.

In both of the systems described heretofore, the 25 total pressure obtaining in the bellows is the sum of the partial pressures of the volatile fluid and the secondary gas so that the switch is operated in response to predetermined values of said total pressure.

30 When the ambient temperature is high, the partial pressure exerted by the secondary gas is relatively high so that the pressure of the volatile fluid and temperature of the evaporator are relatively low when the switch is actuated. When the ambient temperature is reduced, the partial pressure of the secondary gas is reduced and the partial pressure of the volatile fluid and the temperature of the evaporator are relatively high as the switch is actuated.

40 From the foregoing, it will be apparent that I have provided an improved refrigerating system wherein compensation is effected for different rates of heat leakage into the refrigerated chamber due to varying temperatures exteriorly of the 45 chamber, so that the temperature of the refrigerated media is maintained substantially constant.

I have described my invention in connection with a refrigerating system of the compression type, but it is to be understood that it is not so limited and may be applied equally well to other 50 forms of thermostatically controlled refrigerating apparatus.

While I have shown my invention in several forms, it will be obvious to those skilled in the 55 art that it is not so limited, but is susceptible of various other changes and modifications without departing from the spirit thereof, and I desire, therefore, that only such limitation shall be placed thereupon as are imposed by the prior art 60 or as are specifically set forth in the appended claims.

What I claim is:

1. In refrigerating apparatus, the combination 65 of means defining a zone to be refrigerated, a cooling element for abstracting heat from said zone, means for circulating refrigerant through the cooling element, a control device for starting and stopping operation of the circulating means, expansible means having a portion thereof disposed in heat transfer relation with the cooling element and enclosing first and second fluids, one of which is a volatile fluid whose partial pressure is a function of the temperature of said cooling element at normal operating temperatures and the other fluid being non-condensable at normal

operating temperatures, said expansible means being effective to operate said control device to initiate and terminate operation of the circulating means when the expansible means is subjected to predetermined high and low total pressures, respectively, and means for varying the partial pressure of said non-condensable fluid in response to changes in temperature exteriorly of the refrigerated zone.

2. In refrigerating apparatus, the combination 10 of means defining a zone to be refrigerated, a cooling element for abstracting heat from said zone, means for circulating refrigerant through the cooling element, expansible means having a portion thereof extending into the refrigerated zone and defining a chamber for containing first and second fluids, said first fluid being condensable at normal operating temperatures of the zone so that the pressure thereof varies with the temperature of the zone and said second fluid being non-condensable at normal operating temperatures of the zone so that its partial pressure is substantially unaffected by temperature changes in the zone, a control device actuated by the expansible means for rendering the circulating means active and inactive in response to predetermined high and low total pressures within said expansible means, and means for varying the partial pressure of said non-condensable fluid in response to changes in temperature exteriorly 30 of the refrigerated zone whereby the relation between the total pressure of the fluids in the expansible means and the temperature within the refrigerated zone is varied.

3. In refrigerating apparatus, the combination 35 of means defining a zone to be refrigerated, a cooling element for abstracting heat from said zone, means for circulating refrigerant through said element, a switch movable to closed and open position for respectively energizing and deenergizing the circulating means, expansible means having a portion thereof disposed in heat transfer relation with the cooling element for closing and opening the switch when respective predetermined high and low pressures prevail within the 40 expansible means, said expansible means containing both a volatile fluid, the pressure of which is a function of the temperature within the refrigerated zone and a second fluid, the pressure of which is substantially unaffected by the temperature of the refrigerated zone, and means responsive to the temperature exteriorly of the zone for varying the pressure of the second fluid whereby the relation between the total pressures within the expansible means at which the switch is operated and the temperature of the volatile fluid is varied.

4. In refrigerating apparatus, the combination 45 of means defining a zone to be refrigerated, a cooling element for abstracting heat from said zone, means for circulating refrigerant through said element, a switch movable to closed and open position for respectively energizing and deenergizing the circulating means, expansible means having a portion thereof disposed in heat transfer relation with the cooling element for closing and opening the switch in response to predetermined high and low pressures obtaining within the expansible means, said expansible means containing a volatile fluid whose pressure 50 is a function of the temperature of said cooling element and an inert gas whose pressure is substantially unaffected by the temperature of the cooling element, and means responsive to the temperature exteriorly of the zone for varying

the relation between the pressures exerted by the volatile fluid and the inert gas, whereby the temperatures and pressures of the volatile fluid at which the switch is operated are varied with changes in temperature exterior of the zone.

5. In refrigerating apparatus, the combination of means defining a zone to be refrigerated, a cooling element for abstracting heat from said zone, means for circulating refrigerant through the 10 cooling element, an expansible bellows, a conduit connected to said bellows and disposed in heat transfer relation with the cooling element, said bellows and conduit defining a closed chamber for enclosing both a volatile fluid whose pressure varies with the temperature of the cooling element and an inert gas whose pressure is substantially unaffected by the temperature of the cooling element, a switch for controlling operation of the circulating means and closed and opened by said bellows in response to respective predetermined high and low pressures therein, and means for varying the pressure of the inert gas in response to changes in temperature exteriorly of the zone, whereby the relation between the total pressure in the closed chamber and the temperature of the volatile fluid therein is varied as the temperature exteriorly of the zone varies

6. In refrigerating apparatus, the combination of means defining a zone to be refrigerated, a cooling element for abstracting heat from said zone, means for circulating refrigerant through said element, a switch movable to closed and open position for respectively energizing and deenergizing the circulating means, a bellows for closing and opening the switch in response to predetermined high and low pressures in the bellows, a conduit communicating with the bellows and disposed in heat transfer relation with the cooling element, an expansible member disposed exteriorly of the refrigerated zone and communicating with said bellows and conduit, means for compressing and expanding the expansible member in response to respective increases and decreases in temperature exterior of the zone, said bellows, expansible member and conduit defining a closed chamber for containing both a volatile fluid whose pressure is a function of the temperature of the cooling element and an inert gas whose pressure varies with expansion and contraction of the expansible member, and is substantially independent of the temperature and pressure of the volatile fluid.

7. In refrigerating apparatus, the combination of means defining a zone to be refrigerated, a cooling element for abstracting heat from said zone, means for circulating refrigerant through said element, a switch movable to closed and open position for respectively energizing and deenergizing the circulating means, a bellows for closing and opening the switch in response to predetermined high and low pressures in the bellows, a conduit communicating with the bellows and disposed in heat transfer relation with the cooling element, and a vessel disposed in heat transfer relation with the atmosphere exteriorly of said zone, said bellows, conduit and vessel defining a closed chamber for containing both a volatile fluid whose pressure is a function of the temperature of the cooling element and a gas whose pressure is substantially unaffected by the temperature of the cooling element, said vessel containing an absorbent material in which the gas is soluble in amounts bearing a relation to the temperature of the absorbent material, whereby the relation between the pressures of the gas and fluid in the bellows varies with changes in temperature exteriorly of said zone, and, therefore, the temperature of the cooling element at which the circulating means is started and stopped is varied inversely with the changes in the exterior temperature.

8. In a temperature control system, the combination of means defining a zone whose temperature is to be maintained within predetermined limits, heat transfer apparatus associated with said zone, expansible means for controlling the operation of said heat transfer apparatus, a portion of said expansible means being subjected to the temperature produced by said apparatus, said expansible means containing a volatile fluid whose pressure is a function of the temperature produced by the heat transfer apparatus and also containing a gas whose pressure is substantially unaffected by the temperature produced by the heat transfer apparatus, and means responsive to the temperature of a region exteriorly of said zone for varying the pressure of the gas within the expansible means whereby the relation between the total pressure in the expansible means and the pressure of the volatile fluid therein is varied as the temperature of the region exterior of said zone varies.

GRAHAM S. McCLOY.
